UNITED STATES PATENT OFFICE.

CHARLES W. FISHER, OF SPRINGFIELD, OHIO.

LIFTING-JACK.

1,305,455.

Specification of Letters Patent. Patented June 3, 1919.

Application filed December 16, 1915. Serial No. 67,256.

To all whom it may concern:

Be it known that I, CHARLES W. FISHER, a citizen of the United States, residing at Springfield, in the county of Clark and State 5 of Ohio, have invented certain new and useful Improvements in Lifting-Jacks, of which the following is a specification.

My invention relates to improvements in lifting jacks, and it more particularly relates to a pawl and ratchet type of jack in which a step-by-step movement is given to the jack bar in either direction.

An object of my invention is to provide means whereby the action of the pawl and ratchet mechanism may be readily reversed in a simple and effective manner.

A further and more specific object of the invention is to provide means for reversing the pawl and ratchet action which means is located in convenient reach of the operator 20 upon the operating lever of the jack.

A further object of the invention is to provide means for readily releasing the jack bar to permit the same to be brought back to 25 its lowermost position for storing purposes after the load is removed.

A further object of my invention is to provide for indicating the limit of raising movement of the jack bar in order to prevent 30 straining of the parts.

A further object of the invention is to simplify and make more effective the operation of devices of this character.

In the accompanying drawings:—

35 Figure 1 is a side elevation of a jack embodying my improvements, the side of the housing inclosing some of the operating parts being removed; the parts being shown in raising position with the lever at the 40 lower end of its stroke.

Fig. 2 is a rear elevation of a portion of the main standard and jack bar showing the indicating device.

Fig. 3 is a section on the line 3—3 of Fig. 45 2 showing the indicating device in one position.

Fig. 4 is a similar section showing the indicating device in indicating position.

Fig. 5 is a longitudinal sectional view of 50 the forward section of the operating handle or lever.

Fig. 6 is a top plan view of the same.

Fig. 7 is a longitudinal sectional view of the rear section of the operating handle or 55 lever.

Fig. 8 is an end view of the same.

Fig. 9 is a view of the forward side of the mechanism with the housings and standard broken away.

Fig. 10 is a side view of some of the parts 60 shown in Fig. 1 the parts being shown in raising position with the operating lever at the upper end of its stroke.

Fig. 11 is also a side view of the same parts shown in lowering position, the operating lever being shown at the upper end of its stroke.

Fig. 12 is a view of the same parts also shown in lowering position with the operating lever at the lower end of its stroke.

Fig. 13 is a side elevation of the releasing device for the pawl showing the parts in normal position.

Fig. 14 is a similar view of the releasing devices showing the same in operated position.

Referring to the drawings, 1 represents a standard having a base portion 2 and housings 3 and 4, this standard and the housings forming the inclosure and support for the 80 various operating parts. A jack bar 5, having a lifting head 6 at its upper end, is slidably mounted in the standard and is arranged to be raised or lowered by a train of gearing operated by pawl and ratchet mechanism; 85 the gearing consisting of a pinion 7 fixed on a shaft 8 and meshing with the rack 9 on the forward side of the jack bar, a gear 10 also fixed on said shaft 8 and a pinion 11 meshing with said gear 10 and fixed to a 90 shaft 12, said shaft 12 being operated by the pawl and ratchet mechanism now to be described. The shaft 12 is located in a bearing on the forward side of the standard 1 and extends from the housing 4, within which 95 the pinion 11 is located, to a point within the housing 3 where it is provided with a ratchet wheel 13 fixed rigidly thereto. An operating lever formed in two parts, has its inner or socket member 14 pivoted on said

shaft 12 between the inner wall of the housing and the ratchet wheel, the outer or handle member 15 of said lever being removably connected thereto by the pivoted spring pressed catch 17 which engages the projection 18. Pivotedly connected to the lever member 14 is an operating pawl 19, a flat plate 20 to which is connected a spring 21 bears against said pawl to normally hold the nose 19^a thereof in engagement with the 110 teeth of the ratchet wheel. This plate 20 lies loosely in the lower portion of the housing

3 and has an upwardly extending projection 20^a to which the spring is attached and which extends through a slot in a guide 20^b.

Pivoted on a stud 22 which extends laterally into the housing 3 is a holding pawl 23, this holding pawl being provided with a flat upper surface 23^a. Arranged about the stud 22 between the holding pawl and the inner wall of the housing is a plate 24, 10 said plate 24 having an enlarged opening 25 which encircles the stud so that the plate is floating in character. The spring 21 previously referred to as connected with the plate 20 is also connected with the plate 24. 15 The upper portion of the plate 24 has a laterally projecting flange 26 which lies on the flat surface 23^a of the holding pawl. A plate 27 lies on the projecting flange 26, it being yieldably held in contact therewith 20 by a spring 28 interposed between the plate 27 and the upper part of the housing; a pin 29, the upper end of which is secured to the housing and the lower end of which projects through openings in the plate and 25 flange, serves to prevent lateral displacement of the parts, the openings being of sufficient size to prevent binding of the parts.

Slidably mounted in the member 14 of the 30 lever is a plunger 30, the forward end of which has a lateral projection 31 which projects laterally through a recess 14^a and extends in proximity to the lower portion of the plate 24, the spring 21 serving to hold 35 said plate yieldably against said lateral projection. Located in the lever member 15 is a rod 32 having one end connected to a pivoted trigger in the nature of a bell crank lever, one arm 33 of which is connected to 40 the rod 32 and the other arm 34 of which extends through a slot in the lever member. The forward end of the rod is slidably mounted in a guide 35 and interposed between this guide and a pin 36 on the rod 45 is a spring 37 which serves to normally hold the rod in retracted position. The forward end of the rod is in line with the rear end of the pin 30 when the lever member is assembled, so that when the trigger 34 is 50 pulled rearwardly and the rod 32 projected forwardly it will cause the pin 30 to rock the plate 24 against the tension of the springs 21 and 29. This rocking of the plate will also rock the holding pawl 23 by 55 reason of the contact of the flange 26 with the upper surface of said pawl, for the purpose to be explained. When the trigger 34 is thrown forwardly so as to retract the rod 32, the plate 24 will be rocked in the opposite 60 direction by the spring 21 which in turn throws the pin 30 until the lateral projection 31 thereon contacts with the rear wall of the lateral recess 14^a in the member 14 which thus acts as a stop against the further 65 rocking of the plate 24. By reason of the

spring 21 it will be seen, however, that whatever the position of the parts, the projection 31 will be always in contact with the rocking plate 24 so that when the lever 15 is moved upwardly the plate 24 will be given a rocking motion by the contact of the projection therewith by reason of the fact that the projection will move about the arc of a circle relative to the edge of the plate. 75

The operation as thus far described is as follows:—

Assuming that it is desired to raise the jack bar 5 with a load thereon, the trigger 34 is pulled to the rear which projects the 80 rod 32 and pin 30 forwardly, causing the lateral projection 31 to rock the plate 24 against the tension of the springs, this rocking of the plate also swinging the holding pawl 23 until its nose engages with the teeth 85 of the ratchet wheel 13. The parts are so adjusted that the flange 26 of the plate 24 will assume a slight angular position relatively to the upper surface of the pawl 23, as shown in Fig. 1, so that the pressure of 90 the spring 28 will be brought upon the rear of the pawl 23 so as to hold said pawl in engagement with the ratchet wheel. So soon as the lever is drawn upwardly, the lateral projection 31 contacting with the plate 24 95 will give a further tilt to said plate so as to cause the flange 26 to assume the position shown in Fig. 10 which also tilts the plate 27 and brings a downwardly and rearwardly extending portion 27^a thereof in 100 the path of the forward side of a tail 19^b on the operating pawl 19, which not only serves to positively hold the nose of the holding pawl 23 in engagement with the teeth of the ratchet wheel, but will also assist the spring drawn plate 20 in forcing the nose of the operating pawl 19 back into engagement with the teeth of the ratchet wheel as it ratchets over said teeth. By 105 manipulating the operating lever up and down the required number of times, the jack bar is raised to the desired position through the medium of the gearing heretofore described. 110

To lower the jack bar, the trigger 34 is 115 now thrown forwardly as a result of which the rod 32 is retracted permitting the spring 21 to rock the plate 24 until the lateral projection 31 contacts with the rear wall of the recess 14^a. Assuming that the operating 120 lever has been left at the lower end of its stroke, this brings the parts in the position shown in Fig. 12, in which it will be seen that the nose of the holding pawl 23 has been brought out of engagement with the 125 teeth of the ratchet wheel and is being held out by reason of the angular position assumed by the flange 26 of the rocking plate 24, the weight of the load being held by the pawl 19. If the operating lever is now 130

moved upwardly, the lateral projection 31, contacting as before with the rocking plate 24, tilts said plate until the nose of the holding pawl 23 is again brought into the path 5 of the teeth of the ratchet wheel. In this position of the parts, however, the inclined portion 27^a of the plate 27 lies in the path of the rear portion of the tail 19^b so that so soon as the tail of the pawl strikes this projecting portion it will throw the operating 10 pawl 19 out of engagement with the teeth of the ratchet wheel as shown in Fig. 11, by reason of the pressure of the spring 28 upon the plate 27 which is sufficient to overcome 15 the pressure of the spring 21 upon the plate 20. In this position the plate 27 also assists in holding the pawl 23 in engagement with the ratchet wheel with greater force, as it will be seen that an increased tension is 20 placed upon the spring 28 and as the flange 26 bears on the rear end of the holding pawl the tension of the spring will be transmitted to that point of the pawl. In this position 25 of the parts the rear wall of the slot 25 is hanging on the stud 22 by reason of the downward pressure of the springs 21 and 28 and also the pressure of the lateral projection 31 on the plate 24. In all other positions of this plate 24, however, it is of a 30 floating character as the walls of the slot make no contact with the stud.

In order that the uppermost position of the jack bar may be indicated so that there will be no danger of an undue strain being 35 brought upon the parts, I have provided the upper end of the standard 1 with a recess 40 in which is pivoted an indicator finger 41 the upper end of which is normally spring-pressed outwardly by a spring 42, interposed between the finger and jack bar 5. The jack bar 5 is provided with a recess 43, which when the jack bar has reached the limit of its upward movement, registers with the lower end of the indicator finger so that 45 the spring 42 may throw the upper end thereof out of recess in the standard, which thus indicates the position of the bar. When the bar is lowered the indicator finger will be automatically thrown back to the normal 50 position in the recess. This form of indicator permits the position of the jack bar to be readily determined in places where the light is not sufficient for visual observation.

After the load has been removed from the 55 jack bar, I have provided means for readily returning the bar back to its lowermost position without the necessity of ratcheting it back. The operating pawl 19 is provided with a laterally extending pin 44 and the 60 holding pawl with a similar pin 45. Pivoted to the cover plate 3^a of the housing 3 is a cam lever 46 the lower end of which projects through a slot 3^b in the lower part of the housing within convenient reach of 65 the operator. This cam lever is normally

held by a spring 47 in the position shown in Fig. 13, in which position it is out of the path of the pins 44 and 45. When it is desired to lower the bar the lever is thrown to the position shown in Fig. 14 in which 70 position the cam surfaces thereon will have contacted the pins and thrown both of the pawls out of engagement with the ratchet wheel, after which the bar may be readily pushed down to its lowermost position. 75

Having thus described my invention, I claim:—

1. In a lifting jack, a main operating lever, a lifting bar, a ratchet wheel, an operating connection between said ratchet wheel and 80 said bar, an operating pawl on said lever to coöperate with said ratchet wheel, a holding pawl to coöperate with said ratchet wheel, and a single manually operated device on said lever for controlling said pawls in both 85 the raising and lowering operation of the same.

2. In a lifting jack, a main operating lever, a lifting bar, a ratchet wheel operatively connected with said bar, a pivoted operating 90 pawl on said lever, a pivoted holding pawl, spring operated means for holding said pawls in engagement with the teeth of said ratchet wheel, and a single manually operated controlling device carried by said lever 95 to control the action of said spring operated means in both the raising and lowering operation of the devices.

3. In a lifting jack, a main operating lever, a lifting bar, a ratchet wheel having an operative connection with said bar, a spring pressed operating pawl on said lever, a pivoted holding pawl, yieldable devices associated with said pawls and partly carried by 100 said lever for yieldably holding said pawls in engagement with the teeth of said ratchet wheel upon a raising movement of said bar, means carried by said lever for causing said devices to move said holding pawl out of engagement with the teeth of said ratchet wheel upon the lowering movement of said bar, and means operated by said lever for alternately throwing said pawls into and out of engagement with the teeth of said 105 ratchet wheel upon the lowering movement 110 of said bar.

4. In a lifting jack, a main operating lever, a lifting bar, a ratchet wheel having an operative connection with said bar, a spring pressed operating pawl on said lever, a pivoted holding pawl having a flat upper surface, a spring pressed plate associated with said holding pawl having a flange arranged along said flat surface, and means carried 120 by said operating lever for rocking said plate so as to maintain said holding pawl yieldably in engagement with the teeth of said ratchet wheel during the raising movement of said bar and to alternately throw it into and out of engagement with said ratchet 125 130

- wheel during the lowering movement of said bar.
5. In a lifting jack, a main operating lever, a lifting bar, a ratchet wheel having an operative connection with said bar, a spring pressed operating pawl on said lever, a pivoted holding pawl, a spring pressed plate associated with said holding pawl, together with controlling means on said lever for causing said plate to maintain said holding pawl yieldably in engagement with said ratchet wheel during the upward movement of said bar and to cause it to alternately engage and disengage said ratchet wheel during the downward movement of said bar, and means operated by said plate for releasing said operating pawl from said ratchet wheel during the downward movement of said bar.
- 10 6. In a lifting jack, a main operating lever, a lifting bar, a ratchet wheel having an operative connection with said bar, an operating pawl on said lever, a holding pawl, a single manually operated device operable from said lever for changing the relation of said holding pawl relatively to said ratchet wheel including means for yieldably holding said holding pawl in engagement with the teeth of said ratchet wheel during the raising movement of said bar and for alternately throwing said operating and holding pawl into and out of engagement with said ratchet wheel during the lowering movement of said bar.
- 15 7. In a lifting jack, a main operating lever, a lifting bar, a ratchet wheel having an operative connection with said bar, an operating pawl connected with said lever, a hold-
- ing pawl, a tail piece on said operating pawl, a yieldable member associated with 40 said holding pawls, said member being arranged to contact one side of said tail piece during the lifting movement of the bar and the other side of said tail piece during the lowering movement of said bar. 45
8. In a lifting jack, a main operating lever consisting of an outer and inner member, a lifting bar, a ratchet wheel having an operative connection with said bar, an operating pawl on said lever, a pivoted holding pawl, a spring plate associated with said holding pawl, a slidable pin carried by the inner member of said lever with which said plate is in yielding contact, a spring pressed rod carried by said outer lever member arranged 50 in line with said pin, means for projecting and retracting said rod to cause it to change the position of said plate through the medium of said pin so as to change the relation of said holding pawl relatively to said 55 ratchet wheel.
9. In a lifting jack, a lifting bar, a main operating lever, an operating pawl on said lever having an operative connection to said bar, a holding pawl for said bar, means for holding said pawls in operative relation with said bar, and means independent of said lever for throwing said pawls out of operative relation with said bar to permit said bar to be pushed to its lowermost position. 70

In testimony whereof, I have hereunto set my hand this 13th day of December, 1915.

CHARLES W. FISHER.
